UNITED STATES PATENT OFFICE.

LUCILLE VAN SLYKE, OF NEW YORK, N. Y.

DESIGN FOR AN OUTDOOR WINTER PLAY-GARMENT FOR CHILDREN.

45,035.

Specification for Design.

Patented Dec. 9, 1913.

Application filed September 19, 1913. Serial No. 790,800. Term of patent 14 years.

To all whom it may concern:

Be it known that I, LUCILLE VAN SLYKE, a citizen of the United States, residing in the borough of Richmond, county of Richmond, city and State of New York, have invented a new, original, and ornamental Design for an Outdoor Winter Play-Garment for Children, of which the following is a specification, reference being had to the accompanying drawing, forming part thereof.

The design is for a garment fitting closely to the lines of the figure, with leggins, long sleeves with mittens, and a hood surmounted by ears in imitation of rabbit ears.

Figure I, shows a rear view of a garment illustrating my new design. Fig. II, shows a front view of the same.

I claim:

The ornamental design for an outdoor winter play garment for children as shown.

LUCILLE VAN SLYKE.
